UNITED STATES PATENT OFFICE.

ALONZO B. TURNER AND HUGH A. McMULLEN, OF MOUNT SAVAGE,
MARYLAND.

COPYING-BOOK.

SPECIFICATION forming part of Letters Patent No. 529,977, dated November 27, 1894.

Application filed October 3, 1893. Serial No. 487,108. (No model.)

To all whom it may concern:

Be it known that we, ALONZO B. TURNER and HUGH A. McMULLEN, residents of Mount Savage, in the county of Allegany and State 5 of Maryland, have invented certain new and useful Improvements in Copying-Books; and we do hereby declare the following to be a full, clear, and exact description of the invention, such as will enable others skilled in 10 the art to which it pertains to make and use the same.

The invention relates to books for filing letters or papers in proximity to copies of answers or of other papers to which they have some relation that renders it desirable 15 that they be kept or filed together. It contemplates providing in a letter press book means for attaching original letters in proximity to copies of replies to the same in such 20 manner that the two can be preserved and examined in close connection and in their natural order without covering any part of the face of the originals and also so that the 25 originals shall form an opaque back ground and also a support for the thin transparent sheets usually employed to receive letter press copies whereby the copies on such sheets are more easily read and whereby the 30 sheets are kept from falling down and inwardly toward the back of the book and becoming doubled or folded therein.

The invention consists in the construction hereinafter described and particularly pointed out.

35 In the accompanying drawing the figure is an isometric view of the improved copying book.

Numeral 1 denotes the cover of a letter press copying book and 2 the usual leaves 40 for indexing.

3 denotes the thin transparent sheets or leaves adapted to receive fac-simile copies of replies to letters or of other papers, such as usually made by a press in well known 45 manner. Between these leaves we interpose gummed strips 4 bound like the other leaves in the book. The gum or mucilage denoted by 5 is placed on one side only of the strip.

Its purpose is to provide for securing in the book original papers in close proximity to 50 copies of other papers relating to them in their natural order. The adhesive, which may be of any approved kind, is placed on the right hand or last surface of the strip so that when the original paper has its outer 55 back-edge surface pasted or gummed to said strip its written surface will face the answer or copy when the latter is in suitable position to be read.

By gumming in the originals in the particular manner specified their unwritten backs are utilized as a background for the preceding copy made upon transparent paper. By this means the interference of the succeeding copy with the legibility of its predecessor 65 as experienced in ordinary letter press books is avoided and so also is the interference of the writing on the original since its written face is turned toward the succeeding page and away from its predecessor which is to 70 be read in the case assumed. Our arrangement also provides that the backs only of originals are attached to gummed strips and that said backs are adjacent to the copy sheets that have received preceding copies. 75

6 denotes calendered strips or the like which are less likely to adhere to the gummed strips than the copying sheets. These strips 6 are each interposed between the gummed side of a strip 4 and a sheet 3.

80 Originals made of ordinary opaque paper secured in place between the sheets of thin paper will not fall inwardly as readily as thin sheets but serve to hold the latter in place and to prevent the united weight of 85 such thin flexible sheets from folding and doubling between the covers.

Having thus fully described our invention, what we claim is—

A book provided with leaves adapted to 90 receive transfer copies alternately arranged with gummed strips and having calendered strips interposed between said leaves of copying paper and the gummed strips, the gum of said latter strips being on the side toward the end of the book and a calendered 95

strip interposed between the adhesive surface of the gummed strip and the succeeding page, substantially as set forth whereby the gummed strip may receive the back of the original and be arranged in natural order with respect to the answer and on an opposite adjacent page and the accidental sticking of strips avoided.

In testimony whereof we have signed this specification in the presence of two subscribing witnesses.

ALONZO B. TURNER.
HUGH A. McMULLEN.
